UNITED STATES PATENT OFFICE.

CHARLES BURLEIGH, OF FITCHBURG, MASSACHUSETTS.

IMPROVEMENT IN ROCK-DRILLING MACHINES.

Specification forming part of Letters Patent No. 59,960, dated November 27, 1866.

To all whom it may concern:

Be it known that I, CHARLES BURLEIGH, of Fitchburg, in the county of Worcester and State of Massachusetts, have invented certain Improvements in Machinery for Drilling Rocks, of which the following is a full, clear, and exact description, reference being had to the accompanying drawings, making part of this specification, in which—

Figure 1 is a side elevation of my improved machine for drilling rocks. Fig. 2 is a plan of the same. Fig. 3 is a vertical longitudinal section through the center of the same. Fig. 4 is a transverse section through the machine on the line $x\ x$ of Fig. 1. Fig. 5 is a transverse section on the line $y\ y$ of Fig. 1. Fig. 6 is an enlarged view of the under side of the valve-chest and valve. Fig. 7 is a horizontal section through the center of the same on the line $z\ z$ of Fig. 6. Fig. 8 is a transverse section through the same on the line $w\ w$ of Fig. 6. Fig. 9 is an elevation of one end of the piston-bar with its annular cam detached. Fig. 10 is a detail, to be referred to hereinafter.

In machines for drilling rocks there are several requisites, the principal of which are to give the drill a reciprocating motion toward and from the rock to effect the cutting; to rotate the drill partially at each stroke, and to feed it forward the necessary amount, according to its penetration. It is also desirable, when several drills are operated together upon the same frame, to be able to advance or withdraw them from the work, and that they should have a universal motion, so that they may be pointed in any direction required. The nature of the work to be performed also brings so great a strain on all the parts that reciprocate with the drill that it is of great importance that these parts should be few in number, of simple construction, and possess great strength.

My invention has for its object to accomplish all of the above requisites, as will now be described in such terms that others skilled in the art may understand and use my invention.

In the said drawings, A is the cylinder, within which works a piston driven by compressed air or steam, in a well-known manner. This cylinder is provided with a projecting rib, a , on each side, these ribs fitting into grooves b in a slide or drill frame, B, and on this frame the cylinder and parts connected

therewith are made to advance as the work progresses, as will be more fully described hereinafter. The drill-frame B is beveled on its under side, and slides in a dovetailed recess in a clamp, C, which is constructed as follows: c is an ordinary box, which embraces the column or bar D, upon which the drill is mounted, and is made in two parts held together by screws, by which the box may be secured in the required position. On one portion of this box c is a beveled disk, d, to which is fitted the upper portion of the clamp, which is made in two pieces, A' and B', held together by bolts e and nuts f, by loosening which the machine can be revolved around the disk as a center, or advanced or withdrawn in line with the drill, and it will thus be seen that by means of this clamp a universal motion is obtained, together with a movement toward or from the work. E is the piston-bar, which is attached to the piston g, and carries at its forward end the drill F, the piston-bar being made solid except at its rear end, which is hollowed out for the reception of the feed-screw G, thus making the machine compact. This screw G is secured to and revolves in a bar, h, at the end of the drill-frame B, by which it is supported, as seen in Figs. 2 and 3, and it is held with sufficient friction to prevent its turning when the drill is in operation. i is a winch, by which it may be revolved by hand when required. To the rear end of the cylinder A is secured a hollow tube or casing, H, which acts as a guide for the feed and valve gear, and also for the ratchet which rotates the drill. Upon the rear end of this casing H is screwed a cap, I, containing the feed-nut and ratchet J, either made in one piece or permanently secured together, the nut J being held in place by a washer, 14, which rests against a shoulder on the inside of the cap I, thus allowing the nut to revolve freely, as required.

Instead of the feed-screw passing into the end of the piston-bar, as above described, it may be attached permanently to a ratchet, J, and screw through the bar h; but in that case the feed-screw will project out beyond the drill-frame, rendering the machine less compact. The manner in which a partial revolution is given to the drill after each blow will now be described.

At the rear end of the piston-bar E is cut a spiral groove, j, Fig. 9, into which projects a feather, k, on the inside of a ratchet-ring, l,

through which the piston-bar passes. This ratchet *l* is supported in the casing *H* in a slot in which is pivoted the pawl *m*, which engages with the teeth of the ratchet, in contact with which it is pressed by a spring, *15*. The ratchet is confined on one side by a shoulder, *16*, on the inside of the casing *H*, and on the other side by a washer, *17*, which rests against a shoulder, *18*, and thus allows it to be revolved freely. As the piston-bar moves forward toward the rock, the ratchet *l* is turned, so that the pawl *m* falls into the next succeeding notch, there being more weight and friction on the piston-bar than on the ratchet, in consequence of which the latter is turned as required; on the backward stroke, however, the ratchet is held stationary by the pawl *m*, and the feather *k* causes the piston-bar to be partially revolved by means of the spiral groove *j*. Instead of a spiral groove, however, the piston-bar may be made polygonal in cross-section and twisted, so that in passing through an opening in the ratchet of corresponding form it will be turned as required; or, instead of the piston-bar itself being grooved or twisted, a piece attached thereto may be turned in a similar manner by passing through the ratchet or rotating device. By thus causing the piston-bar, or an attachment thereto, to slide through the ratchet, which effects its partial revolution, instead of having the ratchet attached to and carried forward with the drill-spindle, I am enabled to avoid much of the shock on the working parts, and consequently lessen the liability of their being broken, which is a matter of vital importance in machines of this description.

The valve *K*, through which the compressed air or steam is admitted into the cylinder *A*, and the manner in which it is operated, will now be described. This valve, which is what may be termed a hollow double-acting rotary valve, works in a chest or casing, *L*, (seen enlarged in Figs. 6, 7, and 8,) and is so constructed that the pressure of the air or steam will hold it firmly upon its seat. The valve *K* is formed with two ports, *n*, Fig. 10, which connect with the exhaust-passage *o* in the interior, and is also provided with longitudinal bars or toes *p* of sufficient width to cover the ports *q* in the valve-chest *L*, which communicate with the interior of the cylinder, there being a space, *r*, round the valve, so that the air or steam may pass through the holes *s*, Fig. 6, on both sides, round to either port in the valve-chest. When the valve is in a position to take air or steam at either port, the port at its opposite end will be in such a position that the exhaust will pass through it into the interior of the valve, and this valve being in line with the cylinder, the exhaust air or steam is discharged toward the drill, and serves to blow away the dust or water from the working parts of the machine. The required motion is given to the valve *K* by means of a rod, *t*, which is supported in standards *19* on the casing *H* and cap *I*, and is rocked or partially

revolved by means of the jointed tappets *u* *v*, the lower ends of which project through slots in the casing *H*. These tappets are raised at the required times by means of an annular cam, *M*, secured to the rear end of the piston-bar *E*, which passes under them as the bar *E* is reciprocated, the form of the lower ends of these tappets being such as to give the required motions to the valve. By moving the rear tappet *u* on the valve-rod *t* toward or from the cylinder, the air or steam will be cut off sooner or later, so that the drill may be operated to advantage in any desired position, either vertically or horizontally. Instead of the cam *M* being attached directly to the piston-bar *E*, it may be secured to a piece connected thereto without departing from the spirit of my invention.

The feed of the drill is effected in the following manner: *a'* is a lever, which is pivoted, at *b'*, to the casing *H*, and carries at one end the spring-pawl *c'*, which engages with the ratchet-teeth of the feeding-nut *J*, the opposite end of the lever *a'* passing through a slot, *20*, in the casing *H*, into a position to be struck and raised by the annular cam *M* as it passes beneath it, which thus causes the pawl *c'* to revolve the nut *J* on the screw *G*, which, through the connections described, feeds forward the drill as required. The end of the lever *a'* which passes through the slot *20* is so curved and formed that the annular cam *M* does not lift it sufficiently to effect the feed until after it has raised the tappet *v* on the forward stroke to shift the valve, and by this means I am enabled to regulate the feed to correspond with the penetration of the drill; for if the piston-bar does not advance to a certain point the cam *M* will not raise the end of the lever sufficiently to cause the pawl *c'* to fall into the next succeeding tooth in the ratchet-nut *J*, and consequently there will be no feed of the drill. The valve, however, will be shifted at each stroke without reference to the feed.

What I claim as my invention, and desire to secure by Letters Patent, is—

1. The annular projection *M* upon the piston-bar *E*, or an attachment thereto, for the purpose of operating the valve and feeding device, or either of them, substantially as set forth.
2. The stationary rotating device, when operated by the movements of the piston-bar, substantially as shown and described.
3. The hollow valve *K*, with its chest *L*, arranged to operate in line with the axis of the cylinder, substantially as described.
4. The clamp *C*, consisting of the box *c* and pieces *A'* and *B'*, constructed and operating substantially as described, in combination with the slide or drill frame *B*.

CHARLES BURLEIGH.
